WINDOW LOCK

Edmund Peremi and Louis Toth, Manhasset, N. Y.

Application June 4, 1936, Serial No. 83,459

3 Claims. (Cl. 292—39)

This invention relates to window locks or latches and more particularly to locks or latches for windows of the swinging sash type, such as casement windows.

5 It is an object of the invention to provide a lock mechanism for a casement window of the kind in which the sash swings outward, which can be mounted along the margin of the frame remote from the hinge, which can be operated 10 from the inner side of a screen interposed between the sash and the operator, and which will not interfere with the removal of the screen from the frame.

15 It is a further object of the invention to provide a locking mechanism of simple construction which can be caused to lock the sash securely at a single point or at a plurality of widely spaced points by the mere manipulation of a single operating handle disposed within convenient reach 20 of the operator.

It is a further object of the invention to provide a locking mechanism with a chambered or beveled bolt and keeper arrangement, the function of which is to pull the sash in from a partly 25 opened position by the mere operation of the lock operating handle.

It is a further object of the invention to provide a locking mechanism in which the operating handle acts as a counter-weight to hold the latch 30 closed and to prevent the latch from being worked loose by the wind.

It is a further object of the invention to provide a locking device which employs no springs so that the usual trouble encountered from the 35 breakage of springs is avoided.

It is a further object of this invention to provide a rack and pinion locking device for windows in which the rack and the pinion shall be mounted in a housing member so that without 40 regard to the wear or damage to the window, the locking device cannot become inoperative by dis-association of the rack and the pinion, as the same are held firmly in proper relation by the integral housing in which the parts are mounted.

45 Other objects and advantages will hereinafter appear.

In the drawings forming part of this specification,

Fig. 1 is a fragmentary view in front elevation 50 of a portion of a building wall having a window composed of three swinging sashes mounted in it;

Fig. 2 is a fragmentary sectional view taken on the line 2—2 of Fig. 1 looking in the direction of the arrows;

55 Fig. 3 is a fragmentary sectional view taken on

the line 3—3 of Fig. 1 looking in the direction of the arrows;

Fig. 4 is a fragmentary sectional view taken on the line 4—4 of Fig. 1 looking in the direction of the arrows;

Fig. 5 is a fragmentary sectional view taken on the line 5—5 of Fig. 1 looking in the direction of the arrows;

Fig. 6 is a fragmentary view in front elevation showing substantially the same parts shown in 10 Fig. 5; and

Fig. 7 is a fragmentary perspective view of the parts shown in Figs. 5 and 6, the operating handle being shown in an unlocked position.

In Fig. 1 disclosure is made of a fragment of a 15 building wall 1 having a window frame 2 mounted therein. The window comprises in addition to the frame, an outwardly swinging vertically hinged panel 3, an inwardly swinging upper transom 4, and an inwardly swinging lower sash 5. 20 The screen 6 (not shown in Fig. 1) is mounted to cover the sash 3 at the inner side of the frame.

For the purpose of locking the sash 3 in closed position provision is made of a gear segment 7 25

having an operating handle 8. The segment 7 is mounted upon a bearing pin 9 carried by ears 10 of a guide housing 11 which is mounted on the frame. The gear segment 7 meshes with a rack 12 which is mounted for sliding movement in the channel shaped housing 11. Rods 13 are thread- 30

ed into the rack 12 and extend upward and downward therefrom along the margin of the frame. Rotation of the pinion 7 in a clockwise direction 35

as shown in Figs. 2, 5 and 7 moves the rack 12 and the rods 13 upward to lock the window at a plurality of points, and operation of the handle 8 in a counter-clockwise direction moves the rack 12 and the rods 13 downward to unlock the window. The rack 12 has formed upon one of its 40

sides a projecting bolt 14 which is adapted to be moved into and out of a notch formed in a keeper 15 which projects inward from a stile 16 of the sash. The rods 13 have similar bolts 17 mounted upon them for engagement with keepers 18 carried by the stile 16 adjacent the upper and lower ends of the window. The bolts 17 travel in guide 45

housings 17a. It will be seen that the housing 11 with the rack 12 and pinion or gear segment 7 mounted 50 therein comprises a self-contained locking unit. The relation between the rack and the pinion may preferably be established by the manufacturer, whereupon the self-contained unit may be applied in the field without any adjustment or 55

any risk of inefficient handling by unskilled workers. Furthermore no matter what wear and tear may occur on the window, the rack and pinion of the operator cannot become disengaged and will always remain in their originally set proper relationship.

The weight of the handle tends to swing the handle downward, and the handle is so designed that the movement exerted by its weight is sufficient to overbalance the bolts 14 and 17 and the rods 18, to prevent accidental unlocking.

Each bolt has a beveled face 14a and a straight face 14b and the keeper notch is complementary in shape to the bolt end, except that at the lower end of a straight face 15a provision is made of a short beveled face 15b. The faces 14a and 15b constitute coacting, camming surfaces for forcing the window sash to fully closed position as the bolt is thrust upward by operation of the handle 8.

In the illustrative embodiment the screen 6 is formed with marginal recesses 19 to receive the keepers 18, and with edge recesses 20a to accommodate the bolts 14 and 17. The ears 10 project inward beyond the screen and the handle 8 normally overlies a marginal portion of the screen. A cover plate 20 mounted on the inner face of the screen extends over the recess 19 and over the face of the housing 11. The cover plate 20 has upper and lower flanges 21 and 22 which partially cover the ends of the housing 11 and seal the housing against the admission of insects. When it is desired to remove the screen 6 to permit the window to be cleaned or for any other purpose the screen is unlatched from the frame (the screen latching means not being shown), and the handle 8 is swung to a horizontal position. The screen may then be moved away from the window frames without being in any way obstructed by the handle or by the bolts 14 and 17.

While we have illustrated and described in detail certain preferred forms of our invention, it is to be understood that changes may be made therein and the invention embodied in other structures. We do not, therefore, desire to limit ourselves to the specific constructions illustrated, but intend to cover our invention broadly in whatever form its principle may be utilized.

We claim:

1. In a metal casement window, the combination with a window frame and a swinging sash hingedly mounted thereon to swing outward to an open position, of a notched keeper mounted on the inner face of the sash and a self-contained locking unit mounted on the inner face of the frame, said locking unit comprising a rack, a pinion and an integral channel shaped housing, the base of said channel being secured to the window frame and the sides of the channel extending inwardly of the window opening, the outer side forming a guide for movement of the rack in a definite path, said rack having an integral portion forming a bolt, extending laterally between the sides of said channel and adapted to engage in the notch in said keeper to lock the window, the inner side of said channel having inwardly extending ears, a pivot mounted on said ears parallel to the plane of the window and inwardly of said plane, said pivot forming a mounting for said pinion and a swinging operating handle for rotating said pinion and thereby reciprocating the rack.

2. In a metal casement window, the combination with a window frame and a swinging sash hingedly mounted thereon to swing outward to an open position, of a notched keeper mounted on the inner face of the sash and a self-contained locking unit mounted on the inner face of the frame, said locking unit including a channel shaped housing comprising a base secured to the frame perpendicular to the plane of the window, inner and outer side portions extending inwardly of the window opening, said inner side portion having a flange extending toward the outside of the window, a rack mounted for reciprocating movement along the inner face of said outer side portion, said rack having teeth on its face toward the inside of the window, and having a bolt portion projecting laterally therefrom between said outer portion and said flange of said inner portion, said bolt being adapted to engage in the notch in said keeper to lock the window, inwardly extending parallel ears on the inner side portion of said housing, a pivot mounted between said ears, parallel to the plane of the window and inwardly of said plane, a pinion mounted on said pivot and held in permanent engagement with said rack by its pivotal mounting on said ears of said inner side portion and a swinging operating handle for rotating said pinion and thereby reciprocating the rack.

3. In a metal casement window, the combination with a window frame and a swinging sash hingedly mounted thereon to swing outward to an open position, of a notched keeper mounted on the inner face of the sash and a self-contained locking unit mounted on the inner face of the frame, said locking unit including a channel shaped housing comprising a base secured to the frame perpendicular to the plane of the window, inner and outer side portions extending inwardly of the window opening, said inner side portion having a flange extending toward the outside of the window, a rack mounted for reciprocating movement along the inner face of said outer side portion, said rack having teeth on its face toward the inside of the window, and having a bolt portion projecting laterally therefrom between said outer portion and said flange of said inner portion, said bolt being adapted to engage in the notch in said keeper to lock the window, inwardly extending parallel ears on the inner side portion of said housing, a pivot mounted between said ears, parallel to the plane of the window and inwardly of said plane, a pinion mounted on said pivot and held in permanent engagement with said rack by its pivotal mounting on said ears of said inner side portion, and a swinging operating handle for rotating said pinion and thereby reciprocating the rack, said sash also having additional notched keepers spaced from said first named keeper, said window frame carrying guide housings spaced from said first named housing, bolts mounted in said guide housings and adapted to be engaged with said spaced keepers, and operating rods connecting said bolts with said rack whereby, when said rack is reciprocated by swinging the handle and rotating the pinion, said bolts will be caused to engage or disengage said keeper notches simultaneously.

EDMUND PEREMI.
